ATTORNEY.

UNITED STATES PATENT OFFICE

1,929,995

TOY

Henry I. Somerville, Mill Hall, Pa.

Application December 29, 1932
Serial No. 649,238

3 Claims. (Cl. 46—40)

My invention relates to toys and the main object is to provide a toy constructed in simulation of a fireplace including a hearth and a short open chimney extension through which is normally visible a toy figure of Santa Claus, there being also a toy dog lying before the fireplace and means whereby the said figure in the chimney may be drawn downward through the fireplace to the hearth upon which the dog rises and opens its mouth as if barking. Upon release of the operating means the figure of Santa Claus moves back up through the fireplace and the dog again lies down.

Another object is to provide a toy of this kind in a simple, inexpensive, durable and attractive form and having an extremely simple operating means for bringing about the above action of the figures.

With the foregoing and other objects in view my invention resides in the novel construction and arrangement of parts as hereinafter set forth and claimed, reference being had to the accompanying drawing wherein one practical embodiment of my invention is illustrated for purposes of exemplification and wherein:

Figure 1 is a perspective view of my toy with the figures in their normal positions.

Figure 2 is an enlarged vertical cross section through my toy showing the figure of Santa Claus lowered and the dog raised as described.

Figure 3 is a still further enlarged longitudinal section through the figure of the dog in its raised position and showing also a part of the hearth in section.

Figure 4 is a rear elevation of the pulley and weight elements of the operating mechanism.

Figure 5 is a vertical and medial cross section through the figure simulating Santa Claus showing the operating rod raising his cap.

Figure 6 is a vertical cross section along the line 6—6 in Figure 3, the dog being shown however as in its raised position.

Referring now with greater particularity to the drawing in carrying my invention into practice I provide a supporting frame or housing designated generally at 1 and formed of any suitable material such as cardboard or tin in simulation of a fireplace 2 and hearth 3 painted or otherwise surfaced to simulate brickwork as shown. The hearth 3 is generally rectangular in form preferably tapered on its exposed frontal portion and has downwardly turned marginal flanges 4 forming a cavity 5 beneath. The fireplace 2 comprises the sides 6, back 7, front 8 with

inwardly extended U-shaped firebox portion 9 open at its front 10 and upper end 11 and the top 12 extended upwardly at a medial point in the form of an open-topped chimney extension 13.

A pulley trunion or axle 14 is disposed horizontally in the chimney extension 13 and is journaled at its ends in eyelets 15 in the sides of said extension and a pulley 16 having spaced grooves 17 is fixed centrally on this axle. A figure 18 simulating Santa Claus in appearance is provided and is made of any suitable material either solid or hollow and a pair of elevating cords 19 are attached at one end at 20 to spaced

points on the shoulders or pack of the figure 18, 70 are trained upward over the grooves 17 in the pulley 16 and are secured at their other ends to eyes 21 on the weight 22. This weight normally pulls the figure 18 upward as in Figure 1 until the weight rests on the hearth 3 behind the back 75

23 of the firebox portion 9, the figure 18 in this position, due to the connection of the cords 19 some distance below the head, projecting upward somewhat through the open top of the chimney extension 13 so as to be visible and at the same 80

time hide the pulley 16 from view from the front. A lowering cord 24 is secured at one end at 25 to the lower end of the figure 18 and drops through an eyelet 26 in the hearth 3 and emerges from an eyelet 27 in one lateral flange 4 of the 85

hearth as shown, a pull handle or knob 28 being secured to the outer free end of the cord and the arrangement being such that the figure 18 may be drawn down through the fireplace to the hearth by pulling on the handle 28 as will be 90

readily apparent. In this position the figure 18 is visible through the opening in the front 8 of the fireplace. A connecting cord 29 is secured at one end 30 to an eye 31 on the lower side of the weight 22 and drops through an eyelet 32 95

in the hearth 3 behind the firebox back 23 and then is extended through the aforesaid eyelet 26 and is also secured to the figure 18 at the point 25, this cord simply balancing and guiding the elements in their proper path as they are raised 100 and lowered.

A figure 33 simulating a dog in appearance is provided and preferably, though not necessarily, is formed of a hollow metal body 34 suitably shaped and formed in conventional manner to present a natural and attractive appearance. Front legs 35 are rigidly mounted on the ends of a shaft 37 extended laterally through the body and journaled therein, the

lower ends of these legs being pivotally connected 105

110

place 2 comprises the sides 6, back 7, front 8 with

at 38 to bearing ears 39 secured to or formed integrally with the hearth 3 in such position that the figure of the dog faces the firebox opening 10 at some distance therefrom. The lower jaw 40 of the dog is in a separate piece pivoted at 41 to the body and has a finger 42 extended adjacent a finger 43 secured rigidly on the shaft 37 at a medial point for a purpose to be described. Rear or hind legs 44 are provided and are secured 10 at their upper ends on a shaft 45 extended laterally through the body and journaled in the sides thereof, the lower end of said legs being pivoted at 45 in bearing ears 47 similar to the aforesaid ears 39. The tail 48 is pivoted at 49 to the 15 rear of the body 34 and extends loosely thereinto through an opening 50 and is connected at its end by a link 51 to a crank 52 formed medially in the shaft 45. One of the front legs 35 has an upwardly turned toe or lever 53 to which is 20 secured at 54 one end of a cord 55 which drops beneath the hearth 3 through an eyelet 56 and is rigidly secured at 57 to the lowering cord 24. The length of this cord 55 and the position at which it is connected to the cord 24 is such 25 that as the figure 18 of Santa Claus approaches and reaches the hearth the cord 55 will be drawn outward pulling downward on the toe 53 of the front leg 35. This leg pivoting on the ear 39 will project the dog's body 34 upward and forward to cause the dog to assume an erect standing position and the legs 35 and 44 to rest in natural position. As the forelegs 35 move as 30 described the finger 43 will press upward on the finger 42 swinging the lower jaw 40 downward 35 to open the dog's mouth and simultaneously the crank 52 will pull downward on the link 51 and swing the tail 48 of the dog upward.

Thus it will be seen that as the figure 18 of Santa Claus reaches the hearth the dog rises, 40 opens its mouth as if barking and raises its tail to a realistic position and then upon releasing the handle 28 the figure 18 will move rapidly back up through the fireplace as if scared by the dog and the dog will then resume its normal position. The weight 22 of course returns the figure 45 18 to its normal position while the weight of the figure 33 is sufficient to turn it to its depressed position, it being necessary however that the legs do not reach a dead center position as 50 they are raised as will be understood.

The figure 18 has a vertically or longitudinally extended bore or passage 58 in which is loosely mounted a rod 59 having a knob or enlargement 60 at its upper end adapted to hold it 55 from slipping down and out of the bore and having a foot 61 and its downwardly extended end at same distance below the feet of the figure. The figure 18 is provided with a stocking or toboggan cap 62 of elongated tapered form.

60

65

70

75

made of cloth or similar flexible material and secured by its larger end at 63 over the head of the figure with its tasseled end 64 hanging free. As the figure 18 is lowered to hearth as aforesaid the foot 61 will strike the hearth forcing the rod 59 upward in the bore 58 and causing the knob 60 to raise the tasseled end of the cap 62 upward as shown in Figure 2. This action simulates fear on the part of the figure 18 when the dog 33 rises and enhances the entertaining features of the toy.

While I have herein set forth a certain preferred embodiment of my invention it is understood that I may vary therefrom in minor structural details so as best to construct a practical device for the purposes intended, not departing from the spirit of the invention and within the scope of the appended claims.

I claim:

1. In a toy, a housing simulating a fireplace and hearth, a figure mounted in the fireplace and adapted to be raised and lowered therein, and a figure mounted on the hearth and adapted to be raised as the figure in the fireplace is lowered and to return to its normal depressed position as the figure in the fireplace is raised.

2. In a toy, a housing simulating a fireplace, hearth and chimney, a pulley mounted in the chimney, cords trained over the pulley, a weight connected to one end of the cords, a figure connected to the other end of the cords and normally pulled upward into the chimney by the weight, a lowering cord connected to the figure, a figure pivotally mounted on the hearth facing the fireplace, and a cord connecting the figure on the hearth to the lowering cord whereby said figure will be raised as the figure in the fireplace is pulled downward by the lowering cord.

3. In a toy, a housing simulating a fireplace, hearth and chimney, a pulley mounted in the chimney, cords trained over the pulley, a weight connected to one end of the cords, a figure connected to the other end of the cords and normally pulled upward into the chimney by the weight, a lowering cord connected to the figure, a figure pivotally mounted on the hearth facing the fireplace, and a cord connecting the figure on the hearth to the lowering cord whereby said figure will be raised as the figure in the fireplace is pulled downward by the lowering cord, the said figure on the hearth comprising a body, legs pivotally mounted on the body and pivotally connected at their lower ends to the hearth, one leg having an upwardly turned toe portion to which the said cord is connected, a tail and lower jaw pivoted on the body and means whereby the tail will be raised and the lower jaw lowered as the figure is raised.

HENRY I. SOMERVILLE.
